WILHELM SCHMIDT, OF WILHELMSHÖHE, NEAR CASSEL, GERMANY, ASSIGNOR TO
SCHMIDTSCHE HEISSDAMPE-GESELLSCHAFT M. B. H., OF CASSEL-WILHELMSHÖHE,
GERMANY, A CORPORATION OF GERMANY.

WATER-TUBE BOILER.

1,168,748.

Specification of Letters Patent. Patented Jan. 18, 1916.

Application filed January 25, 1915. Serial No. 4,392.

To all whom it may concern:

Be it known that I, WILHELM SCHMIDT, a subject of the German Emperor, residing at Wilhelmshöhe, near Cassel, Germany, have invented a new and useful Improvement in Water-Tube Boilers, of which the following is a specification.

This invention relates to water-tube boilers, especially of the kind in which a plurality of lower cylinders or drums is connected with one or more upper cylinders or drums, the whole being combined with two passages for the combustion gases, one of them being located at one side of the drum, the other at the other side of the same.

It is old to improve the efficiency of such boilers by means of feed water heaters, as well as by pre-heaters for the air, and furthermore, in order to utilize the furnace gases in the highest possible degree, feed water heater and air heater have already in the prior art been arranged in such a manner that the furnace gases act first upon the feed water heater and then upon the air heater. If such an arrangement is to be employed in connection with boilers having a furnace gas passage at each side, then a feed water heater and an air heater must be provided on each side of the boiler, whereby a corresponding increase of the number of the collecting vessels and of the fittings is entailed. As a consequence, such an arrangement is expensive and, in many cases, difficult of inspection, and finally, considerable attention must be paid to the plant during service.

Now, in the novel combination and arrangement of parts forming the present invention, the feed water heater and the air heater are arranged not in series but parallel to one another, the arrangement being such that the feed water heater is situated in the passage at the one side of the boiler and the air heater is situated in the passage at the other side of the same. The heat still contained in the one half part of the combustion gases coming from the furnace is thus taken up by the feed water heater, and the heat still contained in the other half part of said gases is taken up by the air heater; on the whole, however, the cooling down of the gases in question is exactly as good as if the feed water heater and the

air heater were arranged in series, as hitherto, and the heating of the feed water, as well as of the air, is also just the same as up to now. The effect or efficiency of the combined parts is thus the same as with the before mentioned construction of boilers of the kind in question, but the arrangement is far simpler and far more accessible for inspection and furthermore the two kinds of preheaters mentioned may also be of simpler design. Also herein resides the merit of the present invention.

Water tube boilers of the kind in question are used chiefly for the generation of steam of high pressure, but where such steam is employed, economical reasons render it advisable to employ at the same time a high superheating, the superheating temperature being preferably increased up to the limit given by the necessary durability of the superheater tubes, as well as by the safety of the engine to be driven by the highly superheated high-pressure steam. These considerations make it necessary to provide for a good regulation of the superheating temperature in order to prevent an excess of it.

If a furnace gas passage contains, besides a superheater, also an air heater, no reliable regulation of the superheating temperature is possible, because constant attention must be paid to the degree of heating of the air in the air heater which is acted on by the same combustion gases that act upon the superheater also. If the quantity of these gases is diminished by throttling, the air is at once less heated, which, generally, is contrary to what should occur when the superheater is made to take up less heat from the combustion gases. The heat not taken up by the superheater should then be taken up by the air heater which obviously cannot be done when the superheater and the air heater are arranged in series. If however the air heater and the superheater are arranged in separate passages, arranged respectively parallel with respect to the two sides of the boiler, and if the feed water heater is arranged in the passage containing the superheater, then the quantity of the combustion gases conducted through the passage containing the superheater and the feed water heater may be changed exactly

as may be necessary by the degree of superheating required and the heat not taken up by the superheater may be taken up by the feed water heater without any difficulty and thus a practically perfect utilization of the heat of the combustion gases is attained.

Where a water tube boiler of the kind in question is provided with a superheater and where this superheater is arranged at one side of the boiler, there the best arrangement with respect to the best utilization of the heat of the furnace gases is, as appears from the foregoing statements, to arrange the superheater in the passage containing the feed water heater, provided, high superheating of the steam be intended. High superheating means also that the furnace gases are to leave the superheater with a high temperature. If, for instance, in connection with the steam of high pressure, a superheating of this steam up to from 450 to 500 degrees centigrade is demanded, the temperature of the furnace gases when leaving the superheater will be about 500 degrees C. Cooling down the gases to a considerably lower temperature might be attained either by means of an unproportionally large superheating surface or by letting the superheater work in accordance with the pure counter-current principle. This latter method, however, is not applicable in the cases where a very high superheating is required because those parts of the superheating tubes through which the hottest steam is passing and which thus are least cooled are at the same time those that are exposed to the hottest furnace gases, in consequence of which those tube parts are easily burnt. At the other boiler side, where there is no superheater but a correspondingly larger evaporation surface, there the temperature of the furnace gases is considerably lower. Generally, the temperature of the furnace gases is by about 100 degrees C. higher than the evaporation temperature. Suppose, the boiler is to work with a pressure of 40 atmosphere, then the evaporation temperature will amount to 150 degrees C. and that of the furnace gases will be about 100° C. more, or 350° C. respectively.

It is a simple known rule based upon the physical values for the specific heat of the water, the air, and the combustion gases, that in a feed water heater the combustion gases are cooled down by 2° C. for approximately 1 degree of heating, whereas in a preheater for air the combustion gases are cooled down only by 1° C. for the same degree of heating, provided that the whole volume of said gases is conducted through one or the other heater. The combustion gases may thus be cooled deeper by the feed water than by the air and it is thus a matter of course that the feed water heater is arranged at that side of the boiler where the

combustion gases are hotter; this is, in the case in question, that side where the superheater is located.

Another point to be considered is the fact that attention must be paid to keeping the grate durable and there is thus put a limit to the pre-heating of the air. Generally, the temperature of the pre-heated air led to the grate should not amount to more than about 150° C. In connection with this point of view also the unavoidable variations of the combustion gas temperature render it advisable to arrange the air pre-heater at that side of the boiler where there is no superheater. Every change in the condition of the fire, irrespective of whether the change be an intentional one or caused by the service as such, entails a change in the degree of superheating, as well as in the temperature of the furnace gases leaving the superheater. Now, an increase in the temperature of the furnace gases does no damage to the feed water heater, the only result being a corresponding increase of the temperature of the feed water, may be in connection with a partial evaporation of this water. If, however, the air preheater is exposed to such hot gases, the temperature of the air might be so raised that the grate bars would be no more sufficiently cooled. This danger is considerably less at the other side of the boiler, since the temperature of the water-tubes and of the water within them remains approximately the same and the variations of the temperature of the waste gases leaving the feed water heater are thus, at this side of the boiler, less than at the other side.

If the service is carried through with steam of a lower pressure and a lower superheating temperature, then it is, of course, not of particular importance at which side of the boiler the feed water heater and the air heater are arranged. The boiler in question is, of course, able to produce also such kind of steam but generally a rather high pressure and a rather high superheating temperature should be attained and maintained.

My invention will be better understood by referring to the accompanying drawing in which—

Figure 1 is a vertical section through one embodiment of a boiler constructed according to my invention, and Fig. 2 is a vertical longitudinal section through the upper feed water drum and one of the upper boiler drums, in combination with some of the pipes connecting these two drums.

This form of construction of a water tube boiler of the kind in question is specially suited for vessels, but may be employed also in stationary plants.

Referring to said figures, the steam boiler proper consists of the two upper drums *g* and *h*, the two lower drums *i* and *k*, and

the water tubes *l* connecting on one side the drums *i* and *g* and on the other side the drums *h* and *k* with each other. The grate *m* is situated between the drums *i* and *k*. 5 *o*, *p* and *g* designate the parts constituting the feed water heater, *o* being the upper drum of the same, *p* the lower drum, and *g* the tubes. Between the tubes *g* of the feed water heater and the left-hand set of the 10 tubes *l* of the steam boiler proper is arranged the superheater *n*, this latter and the feed water heater being thus located at one side of the boiler, in the same passage, whereas the other side of the boiler is furnished 15 with the air heater *v*, which is situated opposite to the feed water heater. The left-hand set of the water tubes *l* is considerably smaller than the right-hand set, first in order to afford the necessary space for 20 the reception of the superheater and, second, in order to abstract considerably less heat from the fire gases streaming forth from this side of the grate for the purpose of having correspondingly more heat at disposal 25 for the superheater.

The cold water is introduced at *t* into the lower drum *p* of the feed water heater and the steam produced is taken off the boiler from the upper drum *o* at *u*. This drum 30 is connected by pipes *r* and *s* with the upper drum *g* of the boiler proper, as well as with the upper drum *h* of the same, the pipes *r* serving for conducting the hot feed water from the drum *o* to and into the drums

35 *g* and *h* and the pipes *s* serving for conducting the steam from these drums to the drum *o*. Owing to these objects of said pipes, the pipes *r* extend somewhat down into the drums *g* and *h* and the pipes *s* extend somewhat up into the drum *o*, and over these upwardly projecting ends of the pipes *s* is a 40 baffle-plate *e* also located within the drum *o* and serving for catching up the water carried by means of, and with, the steam from the drums *g* and *h* to and into the drum *o*.

45 Of course, other means than a baffle-plate may be provided for separating the water from the steam. At any rate, the possibility of water being carried upward by the steam within the tubes *s* is but small, as these tubes 50 are rather narrow. The steam escaping at *u* is conducted, of course, through the pipes constituting the superheater whence it is led

to the engine in order to drive the same. I wish it to be understood that the steam need 55 not necessarily be taken off the drum *o* but it may be taken off the drums *g* and *h*, these drums being then connected with the superheater.

There are provided, left-hand and right-hand from the drum *o*, dampers *w* and *x*, serving for regulating the flow of the furnace gases through the left-hand and through the right-hand half of the boiler. In other words: the damper *w* serves for 60 regulating the flow of the furnace gases around the tubes of the superheater and of the feed water heater whereas the damper *x* is intended solely for the regulation of the flow of the furnace gases through the air heater. The air is made to pass through this heater preferably in opposite direction to the furnace gases. It is obvious that the more the damper *w* is opened and the damper *x* closed, the larger will be the 65 quantity of the furnace gases acting upon the superheater, as well as upon the feed water heater, but if the position of the dampers *w* and *x* is the reverse, then an approximately larger volume of the furnace 70 gases will pass through the air heater. The dampers in question are, of course, adjusted with proper consideration to the effects to be attained, as already explained in the first 75 part of the present specification.

Having now described my invention, I claim:

In a water tube boiler, in combination with a pair of lower drums and an upper drum, two sets of water tubes connecting the lower drums with the upper drum one set being smaller than the other set, a flue laterally of each set of water tubes, a feed water heater in the flue adjacent to the smaller set of tubes, a steam superheater between the feed water heater and the smaller set of tubes and in the same flue, and an air heater in the flue adjacent to the larger set of tubes.

In testimony whereof I have hereunto set 100 my hand in the presence of two subscribing witnesses.

WILHELM SCHMIDT.
